UNITED STATES PATENT OFFICE.

LEE HALL, OF CHICAGO, ILLINOIS, ASSIGNOR TO FEDERAL ELECTRIC COMPANY, OF CHICAGO, ILLINOIS, A CORPORATION OF ILLINOIS.

ELECTRIC LANTERN.

Application filed November 27, 1922. Serial No. 603,428.

To all whom it may concern:

Be it known that I, LEE HALL, a citizen of the United States, and a resident of Chicago, county of Cook, and State of Illinois, have invented certain Improvements in Electric Lanterns; and I do hereby declare that the following is a full, clear, and exact description thereof, reference being had to the accompanying drawings, and to the letters of reference marked thereon, which form a part of this specification.

This invention relates to improvements in electric lanterns and consists of the matters hereinafter described and more particularly pointed out in the appended claims.

The object of the invention is to produce an electric lantern primarily designed for use by railroad employees, as conductors, brakemen, car inspectors, and the like, which is simple in construction and cheap and economical in manufacture, which is readily folded into compact form; which has a yielding shock absorbing base so that it may be handled and used with the minimum danger of breakage or derangement when dropped; and which is so constructed that it may be easily changed or altered to be used either as a signal lantern or as an inspection lantern.

These and other objects of the invention will more fully appear as I proceed with my specification.

In the drawings:

Fig. 1 is a view representing a side elevation of my improved electric lantern as it appears when in use.

Fig. 2 is a detail horizontal section through the lantern in a plane indicated by the line 2—2 of Fig. 1.

Fig. 3 is a front elevation of the parts shown in Fig. 2.

Fig. 4 is a view on an enlarged scale representing a vertical central section through the lantern in the plane of the pivotal axis of the bale.

Fig. 5 is a detail elevation of the bottom part of the lantern showing the guard for the globe, opened up to facilitate the removal of the lamp and of the globe.

Fig. 6 is a bottom plan view of the lantern as it appears when looked at from below.

Fig. 7 is a top plan view of the part of

the lantern located below the line 7—7 of Fig. 4.

Fig. 8 is a view representing a horizontal section through the lantern in a plane indicated by the line 8—8 of Fig. 4.

Fig. 9 is a bottom plan view of the terminal end of the battery used in the lantern.

Fig. 10 is a part vertical sectional view of the bottom end of the lantern illustrating as it appears with a large secondary reflector attached thereto.

Fig. 11 is a horizontal sectional view taken on the line 11—11 of Fig. 10.

Referring now to that embodiment of the invention illustrated in the drawings:—15 indicates the body of the lantern; 16 indicates the bale; 17, 17 indicate three legs 70 which are inclined outwardly from the body and provide a wide, ample base; and 18 indicates the electric bulb which is the lighting member of the lantern.

The body of the lantern consists of a 75 cylindrical metal shell, which has an integral, closed top 15^a and which is open at the bottom, with a flaring, outwardly extending flange 15^b arcuate in transverse cross section. 19 indicates a hinged bottom 80 closure for the open end of the shell. This consists of a flat disc of insulation material, such as hard rubber, of a diameter adapting it to fit easily within the shell 15. Said disc 19 is held in place by means of a heavy wire 85 ring 20, which is hinged to the flange 15^b at one side and is detachably latched to said flange at a point diametrically opposite to the hinge.

As shown in Fig. 6, the hinge connection 90 of the ring 20 is provided by two spaced ears 21, 21, perforated to receive the ring and riveted to the flange 15^b. The latch consists of a metal piece 22 with a comparatively long journal part 23 (see Figs. 95 2, 3 and 10) having bearing on the ring and of an arcuate hook 24 adapted to engage the arcuate top surface of the flange 15^b. A thumb screw 26, threaded through the hook 24, extends radially through a hole in the flange 15^b to a seat 27 in the journal part 100 23 of the latch and retains the latch in hooked relation with the flange 15^b. The hook 24 has an upright lug 25 with a curved notch 25^a which is opposed to and complements the arch or hollow 26^a in the head of

the thumb screw, thus forming a circular opening to receive the hasp of a padlock 28, shown in dotted lines in Fig. 2. The said hasp will manifestly lock the thumb screw 5 against withdrawal and thus lock the latch against detachment from the flange 15^b.

The three legs 17 are carried by the ring 20 at points spaced at equal arcuate distances apart. Each leg 17 consists of a piece 10 of heavy wire bent in the form of a triangle having a base 17^a and equal sides 17^b, 17^c. The top ends of the side members 17^b are bent upon themselves to form eyes 17^c to receive the ring 20 and are then 15 brought inwardly beyond said eyes, thus providing short horizontal arms 17^d which engage against the bottom of the disc 19 and act to support and retain the said disc within the ring 20. One of the legs 17 is 20 located with its eyes and arms—17^c, 17^d—between the ears 21, 21, to which the ring 20 is hinged. This determines the location 25 of the other legs on the ring 20. When the lantern is in use, the legs 17 are spread apart as indicated in full lines in Fig. 1, so that the bases 17^a of the triangular legs provide an ample base for the lantern.

The bale 16 is pivoted to the lantern body 15 in such manner that it may be swung in 30 one direction from a vertical position above the body, as shown in full lines in Fig. 1, to a vertical position below the body, as shown in dotted lines in said figure. The pivotal connection, however, is such that 35 when swung in the opposite direction, as from the position shown in dotted lines to the position shown in full lines, the movement of the bale in that direction will be arrested when it reaches the vertical position 40 and it is immovable in that direction beyond the said vertical position. The bale 16 is preferably made of rattan or the like, and is of sufficient thickness to give a comfortable grip for the hand. It is fixed at 45 its ends in metal socket arms 16^a, 16^b. Said arms, 16^a, 16^b, are pivoted to the shell 15 by means of right and left threaded bolts or screws 29, 30, which turn with the bale. Each bolt is threaded through a sleeve 31 50 which has a base flange 32 riveted against the inner surface of the shell 15,—the sleeve itself extending through a suitable opening in said shell. The bale arm is locked to the bolt by means of a spring washer 33 which holds the bale arm against the bolt head, so that the bale arm, when it swings, 55 will rotate the bolt. The parts are so arranged that both bolts will be screwed up as tightly as they may be when the bale 60 arms have been brought to vertical position, thus, preventing further movement in that direction. A movement of the bale arms in the opposite direction is possible by reason of the unscrewing movement of the 65 bolts.

The shell 15 is adapted to contain the usual dry cell battery 38^x. Said battery is substantially rectangular in section with rounded corners (see Fig. 9), which engage against the curved sides of the shell. 70 The shell is of such dimensions as to receive the ordinary commercial battery of the kind.

The battery is retained in the shell by the closure 19 and by said closure is held against a yielding, spring backing or stop 75 34 interposed between the top wall 15^a of the shell and the top end of the battery. Said stop consists of a flat disc 35 comprised, as shown, of a metal disc having an insulation covering next to the top end of the 80 battery, and of a helical spring 36. Said spring has an eye 36^a at its bottom end, in which the disc 35 is riveted and a threaded stem 36^b at its top end, which extends through a suitable hole in the top wall 15^a 85 of the shell. The spring is held in place by means of a nut 37, shown in Fig. 1.

The battery has the usual two spring contacts 38, 39, at its bottom end. A flat metal ring 40 carried above the closure 19 is adapted 90 for engagement with the spring contact 38 and a small disc 41 supported, as will presently be described, at the center of and in the plane of the ring 40, is adapted 95 for engagement with the contact 39.

The ring 40 has attached to it three depending pins, 42, 42, 42, which are spaced at angles of 120° about the periphery of the ring and extend through holes in the insulation closure 19. Said closure 19 has a reinforcing circular rib 19^a on its bottom side, the same being enlarged to provide thickened bosses 19^b, 19^b, surrounding the holes through which the pins 42 extend. 100 43 indicates a spacing ring also made of insulation material, the same being concentric with the closure 19 and having a horizontal flange 43^a which engages against the bottom surface of the rib 19^a. Said ring as well as the rib 19^a of the closure 19, has 105 three thickened bosses 44, each spaced at equal distances apart between the enlargements 19^b and provided with aligned holes to receive bolts 45 with thumb nuts 45^x, 110 which secure the spacing ring and closure together. As shown and preferably, the said bosses 44 and the bosses 19^b are so disposed that each boss 44 is located between a pair of arms 17^a on the legs 17, so that said arms engage at each side of said bosses, 115 as shown in Fig. 11, and the legs and discs are interlocked against movement about a vertical axis.

Each of the three contact pins 42 is provided at its bottom end with a contact stud 42^a which is of somewhat larger diameter than the pin itself, thus producing a shoulder at the top of each stud for engagement 120 against the bottom of the boss 19^b, through which the pin extends, to limit the upward 130

movement of the pin. The contact studs are rounded at their bottom ends and normally engage against a flat fibre ring 49 which is held against the bottom of the ring 43. The 5 bosses through which the bolts 45 extend, have reduced ends 44^a, which project below the bottom plane of the ring 43 and extend through arcuate slots 50 in the fibre ring 49. A metallic shell 52 comprising a lamp 10 socket, 52^a, a reflector, 52^b, and a ring flange 52^c, has its ring flange in contact with and riveted to the fibre ring 49. The aforesaid reduced boss ends 44^a project through arcuate slots 52^x in the ring flange 52^c similarly 15 placed to those in the fibre ring 49. The slots permit the insulation ring 49 and the metallic ring flange 52^c to be rotated as a unit a distance equal to the length of the slots 50, 52^x. Spaced from the points normally engaged by the contacts 42^a arcuate 20 distances equal to the length of the slots 50, 52^x—holes 51 are provided in the insulation ring 49 (see Fig. 8). When the unit, comprised of the ring 49 and the ring flange 52^c, 25 is rotated through the arcuate length of the slots 50, 52^x, the holes 51 in the ring 49 will be brought below the contacts 42^a which will drop through the said holes and engage the ring flange 52^c, thus establishing electric 30 connection between the ring 40 and the socket 52^a.

The centrally located disc 41 (which engages the contact 39 of the battery) carries a 35 depending pin 41^a. Said pin extends through a centrally disposed boss in the insulation disc 19 and is provided at its bottom end with a contact stud 41^x of larger diameter, as in the case of the contact stud 42^a. The contact stud and pin 41^x, 41^a, normally hang down with the disc 41 in engagement 40 with the top of the insulation disc 19; but when a lamp plug is inserted in the socket shell 52^a, the central contact of said plug engages the bottom end of the contact stud 41^x and raises it until the shoulder at the top of said stud engages the bottom of the boss through which the pin 41^a extends and arrests further upward movement of the pin. The parts are so designed that this will 50 occur when the disc 41 has reached the plane of the ring 40. The central contact stud 41^x is thus normally always in contact with the lamp plug. A slight turn of the unit comprised of the ring 49, 52^c, which unit 55 constitutes a switch member, will manifestly turn the lamp on or off.

54 indicates a globe which is suspended in place below the lamp bulb 18 by means of a basket comprising three arms, 55, 56, 56, spaced at angles of 120° (see Fig. 6). Said arms have hooks 55^x at their top ends, which are engaged on the bolts 45 and are held thereon against the bottom of the ring flange 52^c by the thumb nuts 45^a. Two of the arms 60 56, 56, are made integral, whereas the other, 65

55, is connected by a suitable eye to the loop in which the bottom ends of said arms 56, 56, terminate, so that the arm 55 is capable of a downward swinging movement to open up a space through which the globe 54 may be removed laterally when desired. 70

The lamp as thus assembled, provides the usual signal light and may be used with or without the globe 54 as desired. The globe 54 may be of white opaque glass or it 75 may be colored, depending upon the signal to be given.

For signal service the reflector 52^a is sufficient. For inspection service, however, a larger reflector is required and I, therefore, provide a second reflector 57 (see Fig. 10) which is much larger than the reflector 52^a. Said reflector, as shown, is made with an apertured base 58 adapted to fit within the reflector 52^a and is otherwise made large 80 enough to embrace and fit upon the top of the shell 15, as shown in Fig. 4. By making the large reflector in this manner it is possible, when the larger reflector is not needed, to mount it on top of the shell 15, as shown 85 in Fig. 4, the reflector being retained thereon by a thumb screw 59 which has a head 60 larger than the aperture in the base of the reflector, and which has a threaded socket 61 adapted to be screwed upon the projecting screw end 36^b of the spring 36 in lieu of the nut 37 heretofore referred to. The reflector is provided with arcuately spaced angle lugs 62 and a ring 63 provided with lug flanges 64 which carry thumb screws 65, 90 is detachably secured to said angle lugs 62 by means of thumb screws, in a familiar manner. When the large reflector is to be applied to the lantern, the thumb nuts 45^a are removed, the basket 55 and globe 54 are 95 taken from the lamp and the ring 63 is applied below the flange 52^c, said ring 63 being provided with suitable apertures for the bolts 45. The thumb nuts 45^a are then 100 replaced and this secures the reflector in position. 105

The spacing ring 43 is of greater diameter than the rib 19^a on the bottom side of the closure 19 with which it is engaged (see Fig. 4) and the inner ends of the arms 17^a 115 of the legs 17 are engaged above the projecting part of said spacing ring, as clearly to be seen in Figs. 4 and 6. By this construction, the legs are held securely against outward swinging movement, since a downward movement of the ring 43 is prevented by the indirect engagement of the bottom closure 19 with the ring 20. Thus, a strong, rigid basis is presented by the legs, which is capable of withstanding any pressure or 120 jar which would tend to spread the legs apart. 125

On the other hand, by reason of the engagement of the arms 17^a against the bottom of the closure 19, and the possibility of 130

upward yielding movement of the closure 19, due to the spring backing or stop 34 interposed between the battery and the top wall of the lantern body, each of the legs 5 may yield to a lateral shock, tending to fold the leg under the lantern body, and all the legs may be forcibly swung together under the lantern bail in a position to be engaged by the bail, as shown in dotted lines in Fig. 10. 1. Such manipulation of the bail and legs brings the lantern into small compass so that it may be easily and readily handled when not in use.

When it is desired to renew the battery, 15 the latch 22 is detached from the flange 15^b and the ring 20 with the closure and its attached parts thereon is swung down into the position indicated in the dotted lines in Fig. 4. The old battery is then removed 20 and replaced by a new one and the parts returned to their first position. The top face of the closure 19, when the parts are in open position, as shown in dotted lines in Fig. 4, presents a flat guiding face for the 25 flat side of the battery when inserted into the body.

By the construction and arrangement of the contact studs and the connecting ring 40 and disc 41^a with reference to the battery 30 above said ring and disc, and the spring stop or backing 34 interposed between the closed top end of the lantern body shell and the top end of the battery, electric contact between the battery and the lamp is always 35 insured. The spring 36 is made quite heavy and acts with sufficient force to always produce the contact referred to, even when the lantern is inverted so that the lamp is above the body,—it being necessary in such case 40 for the spring to be heavy enough to more than support the weight of the battery.

The several advantages of the lantern and its operation are readily apparent from the foregoing description. While in describing it, I have referred to many details of mechanical construction and arrangement, it is to be understood that the invention is in no way limited thereto except as may be pointed out in the appended claims.

50 I claim as my invention:

1. In an electric lantern, the combination of a tubular body, a bail connected to said body, a yielding closure at the bottom end of said body for supporting an electric lamp and a base connected to said body, comprising a plurality of legs having arms engaged with said closure and adapted to yield to lateral shocks or blows.

2. In an electric lantern, the combination of a tubular body, closed at its top and open at its bottom, a bail connected to said body, a closure of insulation hinged to the bottom of said body and adapted to support a battery within the body and to hold a lamp 65 below the body, means for locking said clo-

sure in position, and a base comprising a plurality of legs, each having parts engaging said closure.

3. In an electric lantern, the combination of a tubular body, open at its bottom end, a ring hinged to said open bottom end at one side of said body, a closure of insulation movable with said ring, said closure being adapted to hold a battery within the body, and an electric lamp below the body, and means carried by said ring at a point spaced from its hinged connection for locking said ring to said body.

4. In an electric lantern, the combination of a tubular body, open at its bottom end, a ring hinged to said open end of said body, means for locking said ring to said body, a closure of insulation for the open bottom end of said body, said closure being adapted to hold a battery within the body, and an electric lamp below the body, and a base for said body comprising a plurality of legs hinged to said ring, said legs each having parts engaged with said closure for operatively connecting said closure and ring together.

5. In an electric lantern, the combination of a tubular body, open at its bottom end and closed at its top end, a ring hinged to the open end of said body, means for locking said ring to said body, a closure of insulation for the open end of said body, said closure being adapted to hold a battery within the body, and an electric lamp below the body, spring means carried by the closed top end of the casing for holding the battery against said closure, and a base for the body comprising a plurality of legs hinged to said ring, each leg having parts engaging said closure so that said legs will transmit lateral shocks or blows to said spring means, and will yield under the action of such shocks and blows.

6. In an electric lantern, the combination of a tubular body having a flaring radial flange at its open bottom end, a ring hinged to said flange on one side of the body, a base comprising a plurality of legs hinged to said ring, a closure for the bottom end of said body, operatively connected to said ring through said legs, a hook rotative on said ring at a point opposite its hinged connection with said flange, adapted to engage said flange, and means for locking the hook to said flange.

7. In an electric lantern, the combination of a tubular body having a flaring radial flange at its open bottom end, a ring hinged to said flange on one side of the casing, a base comprising a plurality of legs hinged to said ring, a closure for the bottom end of said body, operatively connected to said ring through said legs, a hook rotative on said ring at a point opposite its hinged connection with said flange, adapted to engage said

flange, and means for locking the hook to said flange, said means including a set screw carried by said hook and adapted to be threaded through the flange and into the bearing of said hook.

8. In an electric lantern, the combination of a tubular body having a flaring radial flange at its open bottom end, a ring hinged to said flange on one side of the casing, a base comprising a plurality of legs hinged to said ring, a closure for the bottom end of said body, operatively connected to said ring through said legs, a hook having a journal rotative on said ring at a point opposite its hinged connection with said flange, said hook being adapted to engage said flange and including a lug with a curved notch and a thumb screw threaded through said hook and flange and into the journal of said hook, said thumb screw having a peripherally grooved head which is opposed to and complements the curved notch in said lug to receive between them, the hasp of a padlock.

25 9. In an electric lantern, the combination of a tubular body, a bail pivoted to said body and adapted to be swung in one direction from a fixed vertical position above the body into a vertical position below the body, a base for the body comprising a plurality of legs hinged to the bottom end thereof, means acting to swing said legs radially outward, said legs being capable of being swung inwardly toward each other into a grouped relation and to be engaged and held by the bail after the same has been swung into a position below the body.

10. In an electric lantern, the combination of a tubular body, open at its bottom end, a closure of insulation hinged to said bottom end, and adapted to support a battery within the body, contact members carried by said closure for engagement with the terminals of said battery, and a combined reflector and lamp socket on said closure below the body, said combined reflector and lamp socket being capable of a limited rotative movement with respect to said closure for making and breaking the circuit from the battery to said lamp.

55 11. In an electric lantern, the combination of a tubular body open at its bottom end, a closure of insulation for said open bottom end of the body, and adapted to support a battery within said body, contact rings on the inner face of said closure adapted for engagement with the terminals of the battery, contact pins connected to said contact rings and extending through said closure, and capable of a limited movement therethrough, and a combined reflector and lamp socket mounted on the bottom face of said closure and capable of a limited rotative movement with respect thereto, said reflector and lamp socket having parts

which in one position of the same are engaged with and are electrically connected to said pins, and which when in another position are disengaged and insulated from said reflector and lamp socket to make and break the circuit from the battery to the lamp.

12. In an electric lantern, the combination of a tubular body, open at its bottom end, a closure of insulation for said open bottom end of the body, adapted to support a battery within said body, contact rings on the inner face of said closure adapted for engagement with the terminals of the battery, contact pins connected to said contact rings and extending through said closure, and capable of a limited movement therethrough, a combined reflector and lamp socket mounted on the bottom surface of said closure, means securing said reflector and lamp socket to said closure but permitting a limited rotative movement between the two, and an insulation ring on said reflector and lamp socket having openings therein, adapted in one position of said reflector and lamp socket to permit engagement and contact of said pins with said reflector and lamp socket, and in another position of the same to disengage and insulate said pins from the reflector and lamp socket.

13. In an electric lantern, the combination of a tubular body open at its bottom end, a closure of insulation for said open bottom end of said body, and forming a support for a battery within said body, contact members carried by said closure for engagement with the terminals of the battery, a combined reflector and lamp socket on said closure, outside the body, said combined reflector and lamp socket being capable of a limited rotative movement with respect to said closure for making and breaking the circuit from the battery to said lamp, a globe engaging the reflector and enclosing the lamp, and a guard basket comprising a plurality of arms secured to said closure, one of which is connected to the other so that it may be swung downwardly to permit removal of said globe from the reflector.

14. In an electric lantern, the combination of a tubular body, open at its bottom end and closed at its top end, a closure for said open bottom end adapted to support a battery in said body, a lamp associated with said closure, a reflector for said lamp, means for securing said reflector to said closure, a second and larger reflector adapted to fit upon the closed top end of the body and to be removably secured thereto, said second reflector having parts adapted to fit within the first reflector and to be secured in position therein by the same means which secure said first reflector to said closure.

15. In an electric lantern, the combination of a body open at the bottom, a closure of insulation for said open bottom, a battery supported by said closure, contact rings on the inner face of said closure adapted for engagement with the terminals of the battery, contact pins connected to said contact rings and extending through said closure and being capable of a limited movement therethrough, a switch member on the bottom of said closure adapted in one position
16. to make electric connection with said contacts, and spring means interposed between the top end of said body and said battery adapted to maintain the engagement of the battery terminals, the several contact members and said switch member.
17. In testimony that I claim the foregoing as my invention, I affix my signature, this 23rd day of Nov., A. D. 1922.

LEE HALL.
